RESERVE TOILET TISSUE CONTAINER

Philip O. D'Ath, Lakewood, Calif.

Application January 3, 1955, Serial No. 33,805

Term of patent 14 years

(Cl. D4—3)

FIG. 1

FIG. 3

Fig. 1 is a side elevational view of a reserve toilet tissue container embodying my new design;

Fig. 2 is a perspective view, and

Fig. 3 is a perspective view as seen from the upper right side of Fig. 1.

I claim:

The ornamental design for a reserve toilet tissue container, substantially as shown.
